FRAME CONSTRUCTION FOR FOLDING CARRIAGES

William C. Troendle, Gardner, Mass., assignor to Thayer, Inc., Gardner, Mass., a corporation of Massachusetts

Application June 2, 1950, Serial No. 165,749

3 Claims. (Cl. 280—36)

1

This invention relates to new and improved frame constructions for folding carriages and the principal object of the invention resides in the provision of a folding carriage having a folding flexible body portion and a folding frame supporting the same, said frame comprising pairs of crossed interpivoted levers of the scissor type which are adapted to hold the flexible body portion extended when latched, and including new and improved devices secured between the crossed levers and the lowermost portion of the folding flexible body to extend the latter downwardly at the bottom thereof and hold this region of the carriage in smooth taut condition when the crossed levers are extended, said devices embodying straps pivoted to the levers and extending above and below the crossing point thereof, and each having an outwardly extending projection thereon lying between the respective pair of crossed levers, said projection being adapted to be contacted and guided by the crossed levers as the latter are extended, so as to hold the straps firmly in desired vertical position providing against displacement of the bottom part of the flexible body portion of the carriage and holding said carriage body taut and smooth.

Other objects and advantages of the invention will appear hereinafter.

Reference is to be had to accompanying drawings in which

Fig. 1 is a view in side elevation of a carriage shown in folded condition;

Fig. 2 is a view on an enlarged scale illustrating the framework in extended condition; and

Fig. 3 is a transverse section through the flexible body portion and illustrating the novel frame construction.

Even though folding baby carriages are extremely satisfactory for their intended purposes, they have a tendency to sag or become creased at the bottom portions thereof and it is proposed to provide frame means to overcome this in a simple but effective manner.

As shown in Fig. 1, there are illustrated wheels 10 supporting undercarriage spring 12 on which at each end thereof is mounted a lever as at 14, 16, in the usual manner. These levers are crossed and interpivoted at 18, and lever 14 rises to be pivoted to the top frame 20 of the carriage as at 22, lever 16 rising in the opposite direction to be interpivoted with relation to the pusher bar or handle 24. The pusher bar or handle 24 is provided with a latch means, as is conventional to hold the frame and body in extended condition. In Fig. 1 the parts are shown in folded condition,

2

but in order to extend the frame and the carriage, it is only necessary to pivot the pusher handle 24 in a counterclockwise direction as indicated by the arrow 26 until it latches with lever 16.

5 Depending from the top frame member 20 there is a folding flexible body portion 28. This body portion has no other support and when the frame 14, 16 is folded, the body portion naturally will fold down above the running gear in the usual 10 manner.

It is understood that the levers 14, 16 appear at each side of the carriage and the construction at each side of the carriage is the same as in Fig. 1.

15 A strap member 30 is pivoted at 18 to the pin that interpivots the levers 14, 16, and the strap is behind the levers, next to the carriage body. This strap depends below the pivot 18 as at 32 and above this point as at 33.

20 The depending portion 32 of the strap 30 is provided at its lower end with a pivot pin 34 swingably engaged with a down-turned ear 36 on a cross bar 38 secured to the bottom of the carriage, see Fig. 3, wherein there is shown a

25 cross rod 40 inside the carriage, the material of the carriage being clamped between the cross bar 38 and the rod 40 as shown at 42.

As thus far described, it will be seen that the strap portion 32 which depends below the pivot point of the levers provides a rigid member which will stretch the lower portion of the carriage body member 28 and maintain the same in desired smooth and taut relation when the crossed levers are extended.

30 33 The upwardly extending portions 33 of the straps 30 are provided with outwardly extending projections 44 located between the levers 14, 16 and in the paths thereof so that when the levers are brought up from the Fig. 1 position to the 40 Fig. 2 position to be extended, the ends of the projections 44 are engaged by the facing edges of these levers and the straps 30 are thereby forced to assume and maintain an upright vertical position due to the fact that the levers 14, 16 assume 45 substantially identical angles with the horizontal.

It will be seen that even though the straps 30 may tilt when the carriage is folded, relieving the pressure on the bottom portion of the carriage body, nevertheless, when the levers are raised to 50 extended condition, the straps 30 must be swung around to a vertical position exerting a downward force on the ends of the bar 38 and maintaining the material of the folding carriage 38 in smooth taut condition from the top rail 20 to the lowermost position thereof.

Having thus described my invention and the advantages thereof, I do not wish to be limited to the details herein disclosed otherwise than as set forth in the claims, but what I claim is:

1. A folding carriage comprising supporting wheels, a scissors type folding frame including a pair of pivoted levers, and a folding body portion, the frame being connected to the body to extend or selectively fold the same, a strap pivoted at the pivot point of the folding frame levers, said strap depending therefrom and connected to the body portion adjacent the lowermost part thereof to hold the same taut, a projection on said strap extending between the levers of the frame and contacted thereby to be centrally positioned with respect thereto to hold the strap vertical when the frame is extended.

2. A folding carriage comprising a flexible folding body, a crossed lever interpivoted supporting folding frame therefor, a rigid cross member on the body at the lowermost part thereof, a member secured thereto and extending from side to side of the body, a strap pivoted to the member at an end thereof, and a projection on the strap for engagement by said levers as the latter are moved from folded to extended condition to center and position the projection and strap to cause the latter to be vertical and extend the lower portion of the body in taut relation.

3. A folding carriage comprising a flexible folding body, a crossed lever interpivoted supporting folding frame therefor, a rigid cross member on the body at the lowermost part thereof, a member secured thereto and extending from side to side of the body, a strap pivoted to the member at an end thereof, and a projection on the strap for engagement by said levers as the latter are moved from folded to extended condition to center and position the projection and strap to cause the latter to be vertical and extend the lower portion of the body in taut relation, said strap being pivoted to the levers at the pivot point thereof, said member having a down-turned ear to which the lower end of the strap is connected.
